Application November 18, 1946, Serial No. 710,564

3 Claims. (Cl. 210—1.5)

1

The invention relates generally to the removal of entrained particles of foreign material from liquid coolant used in machining operations to condition the same for reuse, and it is particularly concerned with the removal of entrained metal chips and abrasive particles, termed "swarf," from the coolant used in abrading operations.

To overcome the disadvantages in the use of filters and settling tanks, continuous magnetic separators have been proposed and, as shown in the patented art, conventionally include electromagnets mounted within a rotating drum with the poles directed outwardly to gather entrained particles from a stream of coolant or the like. In endeavoring to achieve the high flux densities required in practical designs and thereby to increase the percentage of swarf removed from the coolant, it has been considered necessary to resort to the use of windings providing a large number of ampere-turns. While it is true that higher flux densities may be obtained by increasing the current or the number of turns of conductor or both, nevertheless I have found that, as a practical matter, all of such approaches to the problem are accompanied by a number of serious drawbacks.

In increasing the number of turns, for example, it is necessary to provide a correspondingly larger winding space. This may be accomplished in either of two ways, by increasing the radial length of the core or by increasing the pole span and the peripheral spacing between the magnets. The former is objectionable since it not only increases the drop in magnetomotive force in the core itself but also increases the face-to-face area of the legs of the magnet. The latter correspondingly increases the leakage flux between adjacent legs. Since the flux passing directly between the legs follows a path lying within the drum, such flux is totally wasted as far as the magnetic separation process is concerned. Increasing the peripheral spacing of the magnets to accommodate the windings is likewise objectionable since, for a given diameter of drum, it decreases the number of active poles which may be accommodated.

In those cases on the other hand where an attempt is made to obtain increased flux density by the use of higher currents, it has been my observation that inherent disadvantages are of a more serious nature, particularly where the substance being treated is a coolant. It is, of course, well known that the entire amount of electrical energy passing into an electromagnet must be dis-

sipated in the form of heat. It is also a basic phenomenon that, for a given resistance, the heat given off rises at an extremely rapid rate with increased current, increasing as the square of the latter quantity. Thus, a separator using electromagnets is actually a rather inefficient form of electrical heater in which substantially all of the energy is effective to raise the temperature of the coolant. As a result a much larger volume of coolant must be used to obtain an equivalent cooling effect. It might be expected that the amount of heat energy could be reduced by merely using a larger cross section of electrical conductor. Unfortunately, however, a separator 10 of practical size has only a limited volume, and any appreciable reduction in winding resistance must be brought about at the expense of closer magnet spacing (thereby increasing the amount of flux wasted through leakage) or by 15 using inefficient magnetic cores of thin cross section.

During the course of producing the improved separator to be subsequently described, I have found that certain features, not heretofore fully 20 appreciated, are desirable in a coolant separator of the drum type. In the first place such a separator should not raise the temperature of the liquid being treated and should actually assist in cooling it. Secondly, I have found that the efficiency of the separator in removing particles depends to a marked extent on the coordination 25 between the size and shape of the magnets, the spacing between adjacent magnets, and the magnetic conditions existing in the channel adjacent 30 to the poles and through which the liquid flows during treatment.

With the foregoing in view, it is one object of the invention to provide an improved separator of the rotating drum type which effects a continuous and substantially complete removal of 35 entrained metal chips and abrasive particles from a coolant without raising the temperature thereof.

Another object of the present invention is to 40 provide a magnetic separator in which the magnets are not only of a size and shape, relative to the drum, which enables the setting up of high flux densities in the liquid channel but in which the legs are so spaced and proportioned as to 45 enable the flux wasted through leakage within the drum to be reduced to a minimum. More particularly, it is an object to produce a drum type magnetic separator in which the gap between the poles of a given magnet and the spacing 50 of the poles of adjacent magnets is coordi-

nated with the magnetic gap in the liquid channel in a manner to increase the proportion of the total flux made available for separation purposes.

It is a further object to provide a continuous magnetic separator in which commutators, slip rings and similar modes of supplying power to the rotating drum are obviated together with their attendant disadvantages and in which maintenance of the magnetic elements as a result of extended use or as a result of the entry of water or other liquid into the magnet chamber are substantially eliminated. It is a related object to provide a drum type separator which is of simple inexpensive construction and which is inherently durable, giving trouble-free operation for a period normally in excess of the life of the machine tool with which it is used.

Other objects and advantages of the invention will become apparent from the following detailed description of the preferred embodiment illustrated in the accompanying drawings, in which:

Figure 1 is a side elevational view of a separator for liquid coolant embodying the features of the invention.

Fig. 2 is a vertical sectional view of the apparatus taken substantially on the line 2—2 of Fig. 1.

Fig. 3 is a transverse sectional view of the apparatus taken on the line 3—3 of Fig. 2.

Fig. 4 is a perspective view of one of the permanent magnets forming a part of the improved apparatus.

While the invention is susceptible of various modifications and is capable of being practiced with a wide variety of apparatus, I have shown the drawings and will describe herein the preferred form of the invention. I do not, however, intend to limit the invention to such exemplary disclosure but intend to cover all modifications and alternative constructions falling within the spirit and scope of the invention as expressed in the appended claims.

In the course of overcoming the disadvantages of prior art magnetic separators of the drum type, I have found that permanently magnetic material, for example highly retentive sintered magnetic material, may be effectively employed in a novel manner to obtain a number of important practical advantages. It is, of course, recognized that permanent magnets have been used for magnetic separating purposes in the past. For example, magnetic plugs and arrestors of Alnico have been employed to attract and therefore immobilize magnetizable particles in automotive lubricating systems. Furthermore, prior art patents disclosing specific electromagnetic separator structures have contained the suggestion that permanent magnets could be employed in such structure as a less desirable alternative. The latter indicates not only that the advantages residing in the use of permanent magnets have not been appreciated but that such material has been considered and its use rejected. In the discussion which follows, on the other hand, it will be seen that the structure disclosed is such as to fully utilize in a novel and effective manner the inherent characteristics of improved permanently magnetic material.

Referring now to the drawings, the magnetic separator indicated generally at 10 will be seen to consist of a drive portion 11 and a separating portion 12 through which the coolant is directed for treatment. As shown to best advantage in Fig. 3, the coolant from which entrained par-

ticles are to be removed is directed in a relatively thin wide stream through an elongated annular channel 13 defined jointly by the outer peripheral surface of the rotatably supported drum 14 and an arcuate apron 15 partially encircling the drum and which is constructed of iron or other magnetic material. The channel 13 is shown as having the same radial thickness throughout its length. If desired, however, the inlet end of the apron 15 may be spaced slightly farther from the drum 14 than the outlet end, thus producing a liquid stream of gradually decreasing thickness toward the outlet. Such alternative construction has been found advantageous where the liquid vehicle is of a more viscous nature, insuring removal of the finest particles of magnetic material.

To provide the magnetic field for collecting magnetizable particles from the liquid stream, the drum 14 is arranged to carry a plurality of magnet assemblies 16 (Fig. 2) positioned to establish magnetic fields transversely of the channel 13 and movable along the channel upon rotation of the drum. Arcuate sealing members 17, supported at opposite sides of the apron 15 and having sliding contact with the surface of the drum, close the sides of the channel 13 and confine the fluid therein.

As will be seen by reference to Fig. 1 of the drawings, the apron 15 merges at one end into an inlet tank 18 located at one side of the drum and having a baffle 19 over which liquid is discharged into the channel substantially above the rotational axis of the drum. The liquid coolant to be treated is delivered through an opening in the bottom of the tank 18 and an inlet duct 20 by a suitable pump P which draws used coolant through a pipe 21 from the machine with which the apparatus is associated.

Fluid is discharged from the other end of the channel 13 into a discharge tank 22 from which it is carried by a pipe 23 to a sump or reservoir for re-use in the machine. The end of the apron 15 over which the liquid flows into the tank 22 is located substantially below the level of the upper edge of the baffle 19, thus enabling the liquid to flow by gravity through the channel 13 from the tank 18 to the tank 22. The channel 13, of course, remains filled at all times and the relative positioning of the inlet and outlet insures a smooth flow of liquid over the surface of the drum 14.

As shown in Fig. 2, the drum 14 comprises a cylindrical shell 25 of brass, aluminum or other suitable non-magnetic material assembled between circular end plates 26 and 27. Such plates are reinforced by radially extending ridges or vanes 28 connected at their outer ends to an annular flange 29 having axially extending projections 30 thereon which are utilized to support the magnetic elements in peripherally spaced relation.

In accordance with the invention permanent magnets are provided for setting up the magnetic field in the annular space 13, such magnets being so constructed and arranged as both to reduce the loss in magnetism in the magnets themselves (due to the drop in magnetic potential therein) and to reduce the portion of the flux which is lost within the drum due to leakage. In the present instance this is accomplished by the use of magnets 31 which are mounted on the supporting members 29, 30 being fastened thereto by means of throughbolts 32 or the like. As shown in Fig. 2 such magnets 31 are preferably

axially aligned, here four abreast, and polarized in the same direction so as to present a substantially continuous magnetized strip extending the width of the shell 25.

Further in accordance with the invention the legs 31S and 31N of each of the magnets 31 are separated by a gap which is coordinated with the average thickness of the annular channel 13 through which the liquid passes. Referring to the magnet shown in the lowermost position in Fig. 3, the path of useful flux is shown dotted at F, the return path for such flux lying within the apron 15 which, as above stated, is of magnetic material. Interposed in the flux path are two non-magnetic gaps d_1 and d_2 , the lengths of which are determined by the thickness of the annular channel 13. It will be apparent, however, in view of the fact that a magnetic potential difference exists between the poles 31S and 31N, that there will be a tendency for the flux to pass between such poles directly without passing through the apron 15. In the practice of the invention such flux is considerably reduced by so constructing the magnet 31 that the gap G between the poles thereof is at least approximately twice the average distance between the poles of the magnet and the portion of the magnetic apron which is opposite such magnet. Stated another way, the non-magnetic gap G between the poles of an individual magnet should be approximately equal to or somewhat greater than the total nonmagnetic path which the flux must transverse in crossing the gap to the magnetic apron. In accordance with the usual practice in magnetic calculations the drop in magnetic potential through the apron 15 may, for practical purposes, be assumed negligible with respect to the drop across the nonmagnetic gaps d_1 and d_2 .

It might be assumed, using a gap of width G which is just equal to the sum of the gaps d_1 and d_2 , that leakage would take place within the drum across the gap G. While some flux will unavoidably pass directly between the two poles, it is to be noted that the magnetized areas soon acquire tufts 33 composed of magnetic particles or "swarf" which, because of its magnetic nature, become a part of the flux path and correspondingly reduce the total length of the gaps d_1 and d_2 to a value which is much less than the spacing between the drum 14 and the apron 15. With the separator in normal operation and using distances d_1 and d_2 in the proportions shown, it has been found that substantially all of the flux originating in a magnet 31 passes across the gaps d_1 and d_2 and through the apron 15. It has been found further that such radial passage of flux insures that the "swarf" is effectively removed regardless of whether the particles are being carried in the coolant stream adjacent the drum or adjacent the apron. Ordinarily, however, coolant passes through the channel 13 sufficiently rapidly so as to produce turbulence, and this fact facilitates the removal of the particles.

As previously stated, the channel 13 may alternatively be of tapered thickness without departing from the invention. Thus the thickness of the channel 13 at the end or right-hand portion (as shown in Fig. 3) may, if desired, be much less than one-half of the distance of the gap G between the poles. Under such conditions the reluctance of the flux path through the coolant will be considerably less at the end of the channel than the reluctance of the flux path G directly between the poles of the magnet, and consequently very little direct leakage between the

poles will occur. As a given magnet is caused to rotate in a clockwise direction from the end position, the nonmagnetic gap through the coolant will become longer tending to increase the reluctance. However, during the course of such rotation, the magnet acquires an increasing amount of "swarf," and by the time such magnet has reached a left-hand position of the channel, sufficient "swarf" would ordinarily be accumulated to compensate, to a great extent, for the increased reluctance of the flux path. Thus, even though the channel 13 were of tapering thickness, the flux density in the channel 13 would tend to remain more nearly constant and the leakage between the poles of the magnet would continue a constant low value.

Reference has been made to the fact that the nonmagnetic path G between the magnet poles should be coordinated with the spacing between the drum and apron 15. I have also found that the specific structure of the magnet disclosed is a primary factor in the efficient removal of the entrained particles, such structure being shown in detail in Fig. 4. It has been found desirable to construct the magnets 31 with a radial dimension or height which does not exceed the distance between the centers of the poles, which may be referred to as "pole span" and to further shape the magnet in such a way that the flux follows a substantially semicircular path therein. In this way, a maximum difference in magnetic potential between the poles may be achieved with a minimum drop in magnetic potential through the magnet itself due to the reluctance of the latter.

An additional practical advantage of using magnets constructed as shown is the fact that direct leakage between the poles is reduced to a minimum. This can be more fully appreciated by assuming that magnets of a considerably greater height and having long parallel legs were used. Under such conditions such legs would have a correspondingly increased face-to-face lateral extent. Thus, even though a somewhat greater magnetomotive force may be obtained, such effect would be largely dissipated due to leakage between the poles and little, if any, additional magnetism would be produced in the annular channel 13. Conversely, the magnet should preferably not have a height, compared to its pole span, which is much less than that illustrated since this shortens the length of the path within the magnet to too great an extent, thereby reducing the available magnetomotive force at the poles. Referring to Fig. 4, it will also be noted that the yoke portion 31Y of the magnet is larger in cross section than the leg portions or poles 31S, 31N. Such construction reduces the drop in magnetomotive force within the magnets themselves and makes up for the reduction in cross section caused by the holes for the passage of the bolts 32. Still another design feature which has been found to be advantageous is the fact that the pole faces have a rounded contour which very closely matches the peripheral contour of the drum 14. This facilitates the formation of two tufts of "swarf" on each of the poles instead of merely one.

In order to further increase the magnetic efficiency of the separator, the neighboring poles of the adjacent magnets are caused to be of unlike polarity. It is believed that the increased efficiency is due to the flux designated as F' in Fig. 3 which passes across the annular channel 13 and through the apron 15. In order to take full advantage of such additional flux, I have found

that it is desirable to space adjacent magnets by an amount G' as shown. Such spacing should preferably be approximately equal to the gap G between the poles of a given magnet 31 since this tends to reduce flux leakage between adjacent magnets. Gap G' may be somewhat less than the distance, G however, if it is desired to achieve maximum compactness of design.

With the permanent magnets constructed and arranged as shown, it has been found that the two tufts 33 formed on each of the poles are substantially equal in size. This has the advantage that a maximum amount of "swarf" may be built up on each of the poles before the collection reaches a radial height sufficiently great to cause the swarf to drag on the magnetic apron 15. An additional advantage residing in the formation of two tufts is that the latter practically doubles the filtering or screening effect to which additional reference will be made. Studies have shown that the formation of a pair of tufts of magnetic material is facilitated by the use of magnets having pole faces which are relatively great in peripheral extent such as those shown in Fig. 3. This is believed due to the fact that like poles are induced in the tufts at the region thereof adjacent the drum. Since the surface of the drum is well lubricated and since like poles repel, such tufts tend to move as far away from one another as they can without leaving the region of high flux density. Still another contributing factor to the formation of a pair of equal tufts is believed to be the unlike polarity of the neighboring poles of adjacent magnets. As a practical matter it has been found that the formation of tufts in pairs as illustrated greatly increases both the efficiency of the separator in removing the entrained particles and the maximum amount of such material which can be removed per unit time.

The above-described structure, which has been found to be extremely efficient in practice, is contrasted with conventional separators in which a considerable proportion of the available flux is lost within the drum through leakage. This structure is to be particularly contrasted with that employed in electrically energized separators in which the core structure is dictated almost completely by the necessity for linking the magnet with a coil of high ampere-turn capacity. By using the structure shown and by employing sintered highly retentive material, a magnetic separating effect is achieved which could only be achieved in the case of electromagnets by using a considerably larger drum and at a considerably greater manufacturing cost.

In order to cause the magnets to be transported successively to the inlet end and in order to enable the collected swarf to be readily scraped off the drum 14, such drum is supported for rotation about a central axis. Support for the drum is provided, in this instance, by shaft 40 having one end extending through central hubs 41 formed in the respective end plates 26 and 27 and anchored thereto by appropriate set screws 42. The other end of the shaft is journaled in spaced bearings 43 and 44 formed in a housing 45 enclosing the driving portion 11 of the separator.

The driving mechanism indicated at 46 comprises a worm wheel 47 (Fig. 2) loosely mounted on the shaft 40 within the housing 45 and adapted to be driven by a worm 48 fast on a vertical shaft 49. The latter is drivingly coupled to a motor M which, as shown in Fig. 1, is mounted in a 75 to.

vertical position upon a bracket 59 rigid with the housing 45.

The shaft 48 is driven from the worm wheel 47 through a generally well known type of reduction gearing including a stationary ring gear and a planetary pinion. In the present instance the pinion 51, rotatably mounted on an arm 52 projecting laterally from the worm wheel 47, is in mesh with both a stationary ring gear 54 and with a gear 53 fixed to the shaft 40. The gears 53 and 54 are provided with different numbers of teeth, the latter causing the pinion 51 to turn the gear 53 and the shaft 40 at a very slow rate and in a clockwise direction, as viewed in Fig. 1, in response to the rotation of the worm wheel 47.

Due to the magnetic field set up by the magnet assembly 16 in cooperation with the magnetic apron 15, the magnetizable particles entrained in the coolant are attracted to the shell 25 in the vicinity of the magnet pole and collect in a series of tufts 33 standing out from the drum 14 as shown in Fig. 3 and extending lengthwise of the shell transversely of the channel 13. The tufts 33, which gradually increase in size as they are carried forwardly against the liquid stream, form a radial screen across the channel through which the liquid coolant is forced to pass. The collected magnetic particles are thus enabled to mechanically filter out and entrap the nonmagnetic particles entrained in the coolant. It will be understood that some of the nonmagnetic particles normally adhere to the magnetic particles in any case and such particles, of course, are retained in the collected mass.

Continued rotation of the drum eventually withdraws the collected tufts 33 in succession from the liquid stream while fresh masses are formed adjacent magnetic assemblies moved into the vicinity of the channel 13. The operation of the apparatus is thus continuous and newly formed tufts with unimpaired filtering capacity are regularly brought into service. In practice it has been noted that substantially all solid particles are removed from the coolant.

The collected tufts 33 of magnetic and non-magnetic particles may be removed from the surface of the shell 25 in any desired manner. The means provided for this purpose in the exemplary apparatus comprises a scraper blade 56 (Fig. 3) extending lengthwise of the drum and having a sharp forward edge contacting the outer surface of the shell 25. The scraper blade 56 is rigidly fastened to a chute 57 which is pivotally supported on a shaft 58 carried between laterally spaced lugs 59 projecting forwardly from the housing 45. The pivotal axis of the chute 57 is located so that the weight of the chute tends to hold the blade 56 tightly against the shell 25. The collected material is accordingly scraped from the surface of the shell during the rotation of the drum and the chute 57 serves to direct such material into a convenient waste receptacle 61.

A separator constructed as disclosed may be almost continuously operated for a period of several years or longer without requiring attention or maintenance. Because of the absence of any electrical supply, corrosion of slip ring contacts and short circuiting caused by leakage of liquid to within the drum are obviated. At the same time, the improved structure reduces magnetic leakage of flux to a minimum and, for the amount of magnetic material employed, has an efficiency in removing "swarf" which greatly surpasses the prior art separators previously referred to.

This is a continuation in part of the Harry J. Caldwell application Serial 507,270, filed on October 22, 1943, now abandoned, and application Serial 540,818, filed June 17, 1944, now Patent 2,466,839.

I claim as my invention:

1. A separator for effecting the removal of entrained metal and abrasive particles from a liquid coolant used in the operation of an abrading machine comprising, in combination, a rotatable drum having a thin wall of nonmagnetic material, an arcuate apron extending around a portion of said drum and radially spaced therefrom to provide an arcuate channel for the flow of coolant about the periphery of said drum, a plurality of U-shaped permanent magnets mounted within said drum and presenting their poles outwardly against the wall thereof, said magnets being arranged side by side in groups having like poles alined longitudinally of said drum, said alined poles of the several groups being arranged in spaced relation about the circumference of said drum and of alternating polarity, individual ones of said magnets having a substantially semicircular flux path, the height of a given magnet as measured along a radius of said drum being substantially no greater than the span of the poles thereof measured about the circumference of the drum, so that a maximum amount of the drop in magnetomotive force will take place outside of said drum, and a scraper blade riding on said drum exteriorly of said channel for removing collected particles as said drum is rotated.

2. In a separator for effecting the removal of entrained metal and abrasive particles from a liquid coolant used in the operation of an abrading machine, the combination comprising a rotatable drum having a thin wall of nonmagnetic material, an arcuate apron of magnetic material extending around a portion of said drum and radially spaced therefrom to provide an arcuate channel for the flow of coolant about the periphery of said drum, a plurality of U-shaped permanent magnets mounted within said drum and presenting their poles outwardly against the wall thereof, said magnets being arranged side by side in groups having like poles alined longitudinally of said drum, said alined poles of the several groups being arranged in spaced relation about the circumference of said drum and of alternating polarity, individual ones of said mag-

nets having a pole span such that the gap between the poles is at least approximately twice the average distance from the poles of said magnets to said magnetic apron so that the pole-to-pole reluctance of the flux path in the arcuate channel is less than that of the flux leakage path between the poles within the drum.

3. In a separator for effecting the removal of entrained metal and abrasive particles from a liquid coolant used in the operation of an abrading machine, the combination comprising a rotatable drum having a thin wall of nonmagnetic material, an arcuate apron of magnetic material extending around a portion of said drum and radially spaced therefrom to provide an arcuate channel for the flow of coolant about the periphery of said drum, a plurality of U-shaped permanent magnets mounted within said drum and presenting their poles outwardly against the wall thereof, said magnets being arranged side by side in groups having like poles alined longitudinally of said drum, said alined poles of the several groups being arranged in spaced relation about the circumference of said drum and of alternating polarity, said magnets having a pole span and spacing such that the gaps between the poles of individual magnets and between the neighboring poles of adjacent magnets respectively are at least approximately twice the average distance from the poles of said magnets to said magnetic apron so that the reluctance of the magnetic path in the arcuate channel is less than the reluctance of leakage paths between the poles within the drum.
